UNITED STATES PATENT OFFICE.

ARNOLD V. BROWN, OF CHICAGO, ILLINOIS, ASSIGNOR TO KABO CORSET COMPANY, OF CHICAGO, ILLINOIS, A CORPORATION OF ILLINOIS.

ADJUSTING-BUCKLE FOR GARMENT-SUPPORTERS.

1,077,902.

Specification of Letters Patent.

Patented Nov. 4, 1913.

Application filed June 22, 1912. Serial No. 705,234.

To all whom it may concern:

Be it known that I, ARNOLD V. BROWN, a citizen of the United States, residing at Chicago, in the county of Cook and State of Illinois, have invented certain new and useful Improvements in Adjusting-Buckles for Garment-Supporters, of which the following is a specification.

The present invention relates to a buckle or clasp used in connection with a garment supporter for the purpose of adjusting and controlling the length of the strap of said supporter.

The objects of the present invention are to arrange a buckle to which the fabric of the strap may be attached without any stitching or puncturing of said fabric; to provide a buckle which will automatically move to clamping position upon the fabric of the strap when strain is placed upon the strap; to arrange the parts of the buckle so that when strain is placed on the suspending strap the buckle portion is held from swinging out of normal position; and to provide a buckle which is cheap and simple of construction, and which will reduce the amount of material employed in manufacturing the suspending strap.

The invention further consists in the features of construction and in the combination of parts hereinafter described and claimed.

In the drawings, Figure 1 is a vertical section of the buckle of the present invention in operative position; Fig. 2, a front elevation of the parts shown in Fig. 1; Fig. 3, a front elevation of the buckle with the webbing detached therefrom; Fig. 4, a vertical section of the parts shown in Fig. 3; Fig. 5, a face view of a modified form, showing the same in operative position; and Fig. 6, a section of the parts shown in Fig. 5, with the movable portion of the buckle turned outward to permit the threading of the fabric.

Referring to the drawings, and particularly to Fig. 1, the buckle as shown is employed with a suspending strap of a garment supporter. Said strap usually comprises an intermediate section 7 of elastic material, which is joined to an upper section of non-elastic material (not shown) by some suitable means; and the lower end of the section 7, as shown, is looped, and suspended from said loop is a ring or connection 8, to which

is attached any suitable form of clasp used with such devices.

The buckle of the present invention is made in two sections, one of which may be termed the fixed section, and the other the movable section. The fixed section, designated by the numeral 9, consists of a plate-like member which has its edges 10 bent to provide cam or wedge-shaped channels 11, one of said channels being provided upon each side of the plate. These channels are provided with a contracted portion 12 and an enlarged portion 13. The rear or back of the member 9 has integrally formed therewith, or rigidly attached thereto, a U-shaped clip 14, which receives one free end of the elastic section. Said end is placed within said clip in the manner illustrated in Fig. 1 and is clenched in position by subjecting the clip to a swaging operation, bending the free end of the clip toward the body of the member 9. The fabric is brought over the upper edge of the clip and looped back upon itself as best shown in Fig. 1. By this arrangement there is no direct strain upon that portion of the fabric held within the clip, the major portion of the strain being sustained by the edge of the clip. This better insures a practical and efficient securance of the free end of the fabric in position, since it is obvious that danger of the free end pulling out of the clip would be increased were the strain placed directly upon that portion of the fabric held by the clip.

The movable portion 15 of the buckle consists of a plate-like member provided with ears or extensions 16, which rest and slide within the channels 11. This member, as better shown in Figs. 1 and 4, has its ends bent inward toward the fabric, and, as illustrated, has the lower end 17 serrated. At a point intermediate the extremities of this member the body is bent inward as at 18 providing three points of contact between the movable portion and the webbing. As shown in Fig. 1, the fabric when threaded through the buckle lies between the back of the fixed section and the inner face of the movable section, the ends and intermediate portion of said movable section bearing against the fabric.

Owing to the wedge or cam-shaped formation of the channel 11, the tension upon the fabric tending to draw it upward will

draw the movable section upward in the channel, thus augmenting the gripping action of the movable section upon the fabric in proportion to the strain and holding the same more tightly in position. When it is desired to move the fabric for the purpose of adjustment, this can be readily accomplished by forcing the movable section toward the lower end of the channel 11 and into the enlarged portion 13 thereof. This allows the barbed or serrated edge to move away from the fabric, whereby the fabric can be moved up or down as desired. In forcing the movable section to this position the upper bent edge of said section will serve as a finger-piece. After the adjustment has been made, a pull upon the fabric will force the movable member in the direction of strain or upward in the channel 11, and into the contracted portion 12, where it will become wedged and forced into tight engagement with the fabric. The fixed section 9 is cut out as at 19 to permit a threading of the fabric through the buckle. In the initial threading of the fabric through the buckle, shown in Figs. 1 to 4 inclusive, the buckle is forced into the enlarged portion 13 and thence, by slightly pressing upon the upper edge of the movable section, the lower or serrated edge can be moved away from the back of the fixed section, so that a space is provided at the cut-away portion 19, through which the fabric can be passed.

The form of buckle illustrated in Figs. 5 and 6 corresponds in all respects to the form shown in Figs. 1 to 4, save that in the form illustrated in Figs. 5 and 6 the movable member can be rocked or turned, as illustrated in Fig. 6, to permit a threading of the fabric or a movement of the fabric for adjustment purposes. This is produced by forming the ear or extension 16 narrower than the depth of the narrow portion 13 of the channel 12. The same principle of construction, however, is maintained in both devices.

In the arrangement of the present invention, the fabric is secured to the fixed section without the use of stitching or penetrating prongs, which is an item of considerable importance, in view of the fact that the webbing 7 is elastic and a penetration or severance of the elastic strands impairs the life of the webbing. The webbing is threaded in a manner whereby none of the metal which may come in contact with the body of the wearer is exposed, and but one turn in the fabric is needed during the threading operation, thus saving the length of fabric which would be required to weave the free end through the ordinary slotted plate provided for the reception thereof. This results in a material decrease in the

cost of manufacture of the completed article.

The buckle is completely automatic in its action, and, especially with the forms shown in Figs. 1 to 4, the wearer need never even take the trouble to force the movable sections back to clamping position, since the strain upon the fabric will move it automatically. By extending the upper end of the movable section above the upper end of the fixed section in the manner illustrated in Fig. 4, the buckle will be maintained in a straight line. This is an important feature, since it has been found that with the old style of buckle most commonly employed, a strain upon the fabric will tend to swing the upper end of the buckle inward, throwing the lower end out and placing the buckle out of alignment with the fabric, which is highly objectionable for various obvious reasons. This throwing of the buckle is due to the location of the gripping point of the buckle at the upper end thereof. In the present invention the tendency of the buckle to move is overcome by locating the upper edge of the movable section above the upper edge of the fixed section, where it will counteract the tendency of the buckle to move and maintain it in a straight line with the fabric.

I claim:

1. An adjusting buckle for garment supporting straps comprising a fixed plate like member, the sides of said member being bent to overlie the body portion and form oppositely disposed wedge shaped channels, a movable plate like member, ears along the sides of said movable member adapted to slide within said channels, the inner lower edge of said fixed member being cut away to provide an opening for the insertion of the fabric and said channels being widened beyond the ordinary width of the taper for a distance adjacent the lower end thereof whereby when said ears are resting in said enlarged portion the entire body of said plate-like member may be swung away from the fabric about said ears as a center, substantially as described.

2. An adjusting buckle for garment supporting straps comprising a fixed plate like member, the sides of said member being bent to overlie the body portion and forming oppositely disposed wedge shaped channels, a movable plate like member, ears along the sides of said movable member adapted to slide within said channels, the inner lower edge of said fixed member being cut away to provide an opening for the insertion of the fabric, said channels being widened beyond the natural width of the taper for a distance adjacent the lower end thereof whereby when said ears are resting in said enlarged portion the entire body of

said plate-like member may be swung away from the fabric about said ears as a center and the upper end of said sliding member extending when said member is in clamped 5 position above the upper edge of the rigidly secured member, and serving to maintain the buckle in alinement with the fabric, substantially as described.

3. An adjusting buckle for garment supporting straps, comprising a fixed plate like member, the sides of said member being bent to overlie the body thereof and provide wedge shaped channels extending along the sides thereof, a movable plate like member, ears on said member arranged to slide in said channels, said channels being enlarged to a depth beyond the natural depth of the taper and beyond the width of said ears for a distance adjacent its lower end, whereby when said ears are lying within said enlarged portion, the movable section can be turned at right angles to the fixed section and the upper end of the sliding member extending when said member is in clamped 10 position above the upper edge of the rigidly secured member and serving to maintain the buckle in alinement with the fabric, substantially as described.

4. An adjusting buckle for garment sup-

porting straps comprising a fixed plate like member, the sides of said member being bent to overlie the body thereof, and provide wedge shaped channels extending along the sides thereof, a movable plate like member, ears on said member arranged to slide in 15 said channels, said channels being enlarged to a depth beyond the natural depth of the taper and beyond the width of said ears for a distance adjacent its lower end, whereby when said ears are lying within said enlarged portion, the movable section can be turned at right angles to the fixed section and the upper end of the sliding member extending when said member is in clamped 20 position above the upper edge of the rigidly secured member and serving to maintain the buckle in alinement with the fabric, substantially as described.
